UNITED STATES PATENT OFFICE.

RALPH PRATER, OF OAK PARK, ILLINOIS.

GRINDER.

Application filed July 8, 1927. Serial No. 204,549.

My invention relates particularly to grinders of the type adapted for reducing materials of various kinds although not limited to this use alone.

- 5 The main objects of the invention reside in the provision of a simple and effective feeding means for a grinder which is well adapted to maintain a uniform feed, and which is preferably conveniently and accurately adjustable to vary the rate of feed, all with a view toward increasing the efficiency of the grinder by effecting a uniform feed and providing the proper feed for various materials fed to the grinder.
- 10 With these objects in view my invention consists in certain features of novelty in the construction, combination, and arrangement of parts by which the said object and certain other objects hereinafter appearing are effected all as fully described with reference to the accompanying drawings and more particularly pointed out in the appended claims.

In the said drawings—

- 25 Figure 1 is a side elevation of a grinder embodying my invention with parts broken away and in section;

Figure 2 is an enlarged partial section on the line 2—2 of Figure 1;

- 30 Figure 3 is a partial top plan view of the grinder;

Figure 4 is a partial end elevation of the same.

- Like characters of reference indicate like parts in the several views.

Referring to the drawings 1 designates a grinder casing, and extending through this casing is a horizontally disposed revoluble grinder shaft 2. See Figure 1. The casing 40 1 is provided with an end inlet opening 3 disposed in an upright plane above the shaft 2, and the casing is provided with a bottom discharge opening across which is disposed a sizing screen 4. Blades or hammers 5 within the casing 1 and carried and rotated with the shaft 2 serve to reduce material fed into the casing until it is of such size that it discharges through the screen 4. Further description of this portion of the grinder is 45 unnecessary for the present purposes, it being fully described and claimed in my co-pending U. S. application for Letters Patent, Serial No. 175,997, filed March 17, 1927, for improvement in grinder.

- 50 Secured with the casing 1 and inclining downwardly to the inlet opening 3 of the

casing is a feed hopper 6 which is provided with a bottom opening 7 adjacent said inlet opening. A plate 8 is disposed in said opening 7 and continues the bottom of the 60 hopper, and is pivotally mounted at its inner end on the hopper for vertical movement with respect thereto, as designated at 9. A flat spring 11 is secured on the hopper 6 underneath the same and inwardly beyond the inner end of the plate 8, as designated at 12, and is engaged with a block 13 secured to the plate 8 underneath the same for yieldably urging the plate 8 65 downwardly. An eccentric 14 is secured on the shaft 2 underneath the block 13, and the block 13 engages downwardly upon the eccentric 14, so that as the shaft 2 rotates the eccentric 14 and the spring 11 effect a vertical vibration of the plate 8 for the feeding of material in the hopper into the casing 1 through the inlet opening 3 of the casing.

A vertically disposed and vertically movable plate 15 is disposed against the vertical outer surface of the inlet opening end wall 80 of the casing 1, and the lower edge of this plate forms the upper edge of the inlet opening 3, so that this inlet opening may be varied to vary the rate of feed of material into the casing 1. The plate 15 is secured 85 in vertically adjusted position in the following manner. See Figures 1 and 4. A screw 16 is passed outwardly through and is secured in a bore through the inlet opening end wall of the casing 1 and is disposed 90 above the inlet opening 3 in central relation therewith. The screw 16 passes through a vertical slot 17 in the plate 15, and a thumb nut 18 engaged on the outer end of the screw 16 serves to clamp the plate 15 against the 95 casing 1 to secure this plate in vertically adjusted position, the slot 17 permitting vertical adjustment of this plate.

Engaged on the screw 16 between the plate 15 and the nut 18 is a washer 19 which is secured against rotation on the screw 16 in a usual manner, and this washer is provided with diametrically opposite horizontally disposed pointers 20 which cooperate with scales 21 on the plate 15 for predeterminate 100ly adjusting this plate. See Figures 1 and 4.

In operation material in the hopper 6 passes over the plate 8, and rotation of the grinder shaft 2 effects vertical vibration of the plate 8 with the result that a uniform feed of the material into the grinder is ef- 110

fected, the rate of which feed may be varied by the adjustment of the plate 15. The arrangement of the plate 8 adjacent the inlet opening of the grinder is particularly advantageous in that it prevents the clogging of material at the inlet opening because it vibrates the material against the upper edge of the inlet opening and thus works it through the inlet opening, with the result that material consisting of large pieces, such as corn cobs, are passed into the grinder at a uniform rate.

While I have herein shown and particularly described the preferred embodiment of my invention I do not wish to be limited to the precise details of construction shown as changes may readily be made without departing from the spirit of my invention, but having thus described my invention I claim 20 as new and desire to secure by Letters Patent the following:—

1. In a grinder the combination with a hopper inclined downwardly toward its discharge end and provided with a bottom opening adjacent its discharge end, of a plate disposed in said opening and continuing the bottom of the hopper and pivotally mounted at its inner end for vertical movement with respect thereto, spring means 30 yieldably urging said plate in one direction, and means for intermittently operating the plate in the opposite direction for effecting vibration thereof for the feeding of material in said hopper.

2. In a grinder the combination with a grinder casing provided with an inlet opening and a grinder shaft disposed below said opening, of a hopper inclined downwardly to said opening, a vertically movable member adjacent said inlet opening and having an upwardly facing surface disposed correspondingly with the bottom of the hopper and over which material in the hopper passes, and means for vertically vibrating said movable member including a revolute member below said hopper and fast on said shaft.

3. In a grinder the combination with a grinder casing provided with an end inlet opening and a grinder shaft extending longitudinally of said casing and disposed below said opening, of a hopper inclined downwardly to said opening and provided with a bottom opening adjacent said inlet opening, a plate disposed in said opening of the hopper and continuing the bottom thereof and pivotally mounted at its inner end on the hopper for vertical movement with respect thereto, an eccentric fast on said shaft below said plate, a block secured to said plate underneath the same and engaging downwardly on said eccentric, and a flat spring secured with said hopper inwardly beyond the inner end of said plate and engaged with said block for yieldably urging said block and plate downwardly.

4. In a grinder the combination with a grinder casing provided with an end inlet opening disposed in an upright plane and a grinder shaft extending longitudinally of said casing and disposed below said opening, of a hopper inclined downwardly to said opening and provided with a bottom opening adjacent said inlet opening, a plate disposed in said opening of the hopper and continuing the bottom thereof and pivotally mounted at its inner end on the hopper for vertical movement with respect thereto, an eccentric fast on said shaft below said plate, a block secured to said plate underneath the same and engaging downwardly on said eccentric, a flat spring secured with said hopper inwardly beyond the inner end of said plate and engaged with said block for yieldably urging said block and plate downwardly, a second plate disposed upright and vertically movable and forming the upper edge of said inlet opening, and means carried by said casing for adjustably positioning said plate in its said vertical movement.

In witness whereof I hereunto affix my signature this 5th day of July, 1927.

RALPH PRATER.
